(57) **CLAIM**

The ornamental design for an IT rack enclosure door, as shown and described.

DESCRIPTION

FIG. 1 illustrates a downward, front, left side perspective view of an IT rack enclosure door in accordance with the claimed design;

FIG. 2 illustrates a downward, front, right side perspective view of an IT rack enclosure door in accordance with the claimed design;

FIG. 3 illustrates a front view of an IT rack enclosure door in accordance with the claimed design;

FIG. 4 illustrates a top view of an IT rack enclosure door in accordance with the claimed design;

FIG. 5 illustrates a bottom view of an IT rack enclosure door in accordance with the claimed design;

FIG. 6 illustrates a side, left view of an IT rack enclosure door in accordance with the claimed design; and,

FIG. 7 illustrates a side, right view of an IT rack enclosure door in accordance with the claimed design.

The broken lines in the figures show unclaimed portions of the environment, structures, or boundaries of items adjacent to the claimed IT rack enclosure door, and form no part of the claimed design.

1 Claim, 7 Drawing Sheets
